CLAIM

The ornamental design for a display screen having a transitional graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a display screen having a transitional graphical user interface in a first state;

FIG. 2 is a front view of a display screen having a transitional graphical user interface in a second state;

FIG. 3 is a front view of a display screen having a transitional graphical user interface in a third state;

FIG. 4 is a front view of a display screen having a transitional graphical user interface in a fourth state;

FIG. 5 is a front view of a display screen having a transitional graphical user interface in a fifth state;

FIG. 6 is a front view of a display screen having a transitional graphical user interface in a sixth state; and,

FIG. 7 is a front view of a display screen having a transitional graphical user interface in a seventh state.

The broken lines representing features of the display screen having a graphical user interface or portion thereof and the dot-dashed lines showing portions of the display screen form no part of the claimed design.

The appearance of the graphical user interface sequentially transitions between the images shown in FIG. 1-7. The process or period in which one image transitions to another image forms no part of the claimed design.
